OVEN DOOR

James E. Davis and John T. Doner, Marion, Ohio, assignors to Whirlpool Corporation, a corporation of Delaware

Filed Jan. 19, 1967, Ser. No. 610,354
8 Claims. (Cl. 126—200)

ABSTRACT OF THE DISCLOSURE

An oven door having aligned viewing apertures in outer and inner frame sections with each aperture covered by a glass pane for viewing the interior of the oven and with a continuous spacer and seal member between the panes that supplies sealing pressure to each pane and that prevents fluids from entering between the panes and within the confines of the spacer and seal member.

The invention here is embodied in an oven door comprising an outer frame section and an inner frame section spaced apart and each having an aligned observation opening for viewing the interior of the oven from the exterior. In each frame section means are provided for yieldably securing a transparent means such as a glass sheet or pane to span each opening. Means are provided for securing the two frame sections together with the panes in aligned spaced relationship and there is provided an intermediate and continuous substantially fluid impervious spacer and seal member means between the panes extending around the openings adjacent thereto and yieldably bearing against the panes so as to urge them away from each other and provide a dead air space between the panes and within the confines of the intermediate spacer and seal member.

The accompanying drawings illustrate one embodiment of the invention. Of the drawings:

FIGURE 1 is a front elevational view of an oven door embodying the invention.

FIGURE 2 is a rear elevational view thereof.

FIGURE 3 is an enlarged fragmentary sectional view taken substantially along line 3—3 of FIGURE 1.

FIGURE 4 is an enlarged fragmentary sectional view taken substantially along line 4—4 of FIGURE 1.

FIGURE 5 is a perspective view showing the rear of a detail of the inner part of the door of FIGURES 1—4.

FIGURE 6 is similar to FIGURE 5 but showing the opposite side thereof.

The oven door embodiment shown in the drawings comprises an assembly of an outer section 10, exposed to the exterior of the oven (not shown), an inner section 11 at the interior of the oven and an intermediate section 12 between the sections 10 and 11 serving as a spacer and seal member means. Each of these sections which is made up of a plurality of parts can be individually and independently assembled and then the three sections assembled together in completing the door.

The outer section 10 comprises a frame 13 defining an observation opening and which may be made of an extruded metal such as aluminum, a sheet of transparent material such as plate glass 14 secured in the frame 13, a rubber, edge enclosing, resilient bumper 15 and a sheet metal retainer 16 at each of the four corners of the glass, each held in position by a screw 17 extending through the retainer 16 into the frame 13. As can be seen in FIGURES 3 and 4, the frame 13 has an inner edge portion 18 around the edge of the glass 14 and cooperating with the retainer 16 to hold the glass in position. The outer side 19 of the frame 13 forms a flat outer edge of the door and integral therewith is an inwardly extending

2

flange 20 to which the inner section 11 of the door is fastened as by a plurality of screws 21.

The inner section 11 of the door comprises an inner door panel 22 attached to the flange 20 by the screws 21 and having at its periphery an inwardly extending flange 23 located adjacent and inwardly of the side 19 of the door. The inner section 11 also comprises a side frame 24 which is attached to the inner surface of the panel 22 as indicated at 25 with the frame 24 being generally L-shaped in cross section as shown most clearly in FIGURES 3 and 6.

The inner door panel 22 of the inner section 11 presents an inwardly raised part 26 which encloses the peripheral edge of a second transparent sheet which may also be a glass panel 27 covering an observation opening. The opposite side edges of the glass panel or pane 27 are provided with a pair of small U-shaped resilient rubber bumpers 28 (FIGURES 3 and 6) with each being located intermediate the top and bottom edges of the pane 27. These ends 29 are each held within a bracket 30 each of which extends along the pane edge 29 and is attached to the frame 24 by spaced screws 31. As shown in FIGURES 5 and 6, three of these screws 31 are used in the illustrated embodiment at each edge of the glass pane 27.

At the sides of the frame 24 there are provided the two side hinges which are not shown completely as they form no part of the present invention but parts of which are illustrated at 32 to illustrate that these hinge parts, although attached to the inner door section 11, are not attached to the outer door section 10 so that two sections can be independently assembled and then attached together by the above described screws 21. These side hinge parts and the overlying panel 22 contain bottom side openings 33 through which the other (and not illustrated) hinge parts may extend.

As illustrated in FIGURES 3 and 4, the outer and inner glass panes 14 and 27 are spaced apart in order to provide a dead air space 34 sealed by the intermediate section 12 to prevent fluid flow into and out of this space.

The intermediate section 12 is in the form of a resilient metal strip 35 that is continuous to describe a closed figure which in the illustrated embodiment is rectangular. The rectangular strip 35 has one edge 36 at substantially right angles to and adjacent the inner surface of the glass panel 27 and a second edge 37 adjacent and at substantially right angles to the inner surface of the glass pane 14. The portion of the strip 35 between these edges 36 and 37 is at an acute angle to the glass panes 14 and 27, as shown in FIGURES 3 and 4. The strip edges 36 and 37 each carry a resilient rubber sealing gasket 38 and when the door sections 10 and 11 are assembled together, as shown in the illustrated embodiment of the invention, the strip 35 is under compression so that sealing pressure is applied to the panes 14 and 27 through the sealing gaskets 38.

At the opposite sides of the door at about the midpoint thereof, as shown in FIGURE 3, there is provided on each side bracket means comprising a bracket 39 that extends from the strip edge 37 toward but short of the inner section frame 24. This bracket 39 has a flat section 40 located adjacent but spaced from the frame 24. Each flat section 40 is provided with an opening 41 that surrounds but is spaced from the center attaching screw 31 on each side of the door. The flat section 40 and loose fitting operating 41 cooperate with the attaching screw 31 serving as locating pins means to locate the rectangular strip 35 with respect to the glass panes 14 and 27 while permitting relative movement between the strip 35 and the glass panes.

With this arrangement the intermediate section 12 of the door and particularly the distorted resilient rectangular strip 35 and the sealing gaskets 38 provide the dead air

space 34 between the glass panes that can be initially filled with dry air so that moisture will not condense on the glass panes and particularly on the inner surface of the outer pane 14 which would of course tend to prevent observation of the interior of the oven with which the oven door of this invention is used.

As previously described, the side frame 24 shown in detail in FIGURES 5 and 6 is a part of the inner door section 11. This side frame carries the side glass supporting brackets 30. The side frames 24 also carry top and bottom glass retainer strips 42 which are also made of metal. As shown in FIGURE 4, these strips 42 enclose the top and bottom edges of the inner glass pane 27 which is provided with a resilient gasket bumper 43 similar to the side bumpers 28. The top and bottom edge strips 42 are attached to the side frame members 24 by the top and bottom attaching screws in the sets of screws 31 in the inwardly raised part 26 and the inner door panel 22 is attached to the brackets 42 by spaced screws 44.

As can be seen from the above description, the oven door of this invention provides a sealed dead air space between two glass panes so as to prevent moisture condensation which would obscure viewing the contents of the oven through the glass. The door is made up of an assembly of three primary separate parts, the outer section 10, inner section 11 and intermediate section 12. Each of these sections may be separately subassembled and then assembled together to complete the door. When assembled the resilient intermediate section 12 and particularly the resilient strip 35 is distorted so as to press outwardly at the sealing gaskets 38 against the inner surfaces of the glass panes 14 and 27.

The outer pane 14 is retained in position against the frame 13 by the four corner glass retainer plates 16 which not only retain the glass 14 in position but strengthen the frame 13 at the joined corners thereof.

Having described our invention as related to the embodiment shown in the accompanying drawings, it is our intention that the invention be not limited by any of the details of description, unless otherwise specified, but rather be construed broadly within its spirit and scope as set out in the accompanying claims.

The embodiment of the invention in which an exclusive property or privilege is claimed is defined as follows:

1. An oven door, comprising: an outer frame section having an observation opening therein; an inner frame section having an observation opening therein; means for yieldably securing a glass pane in said outer frame section to span its opening; means for yieldably securing a glass pane in said inner frame section to span its open-

ing; means for securing said frame sections together with said panes in aligned, spaced relationship; and an intermediate, continuous, substantially fluid impervious, spacer and seal member means between said panes extending around said openings yieldably bearing against said panes for urging them away from each other and toward their respective frame sections and for providing a dead air space between said panes and within the confines of said intermediate member.

2. The door of claim 1 wherein there are provided bracket means on said intermediate member for positioning said intermediate member relative to a frame section.

3. The door of claim 1 wherein there are provided bracket means on said intermediate member for positioning said intermediate member relative to one frame section and locating means on said one frame section loosely engaging said bracket means.

4. The door of claim 3 wherein said bracket means comprises spaced brackets on said intermediate member extending to adjacent the inner frame section and said locating means comprises pins on said inner frame section loosely engaging said brackets for permitting relative movement therebetween.

5. The door of claim 1 wherein said means for yieldably securing each glass pane comprises a plurality of spaced resilient gasket means embracing the edges of each pane between the respective pane and its frame section.

6. The door of claim 1 wherein said intermediate member comprises a resilient metal strip generally arranged at an acute angle to both panes and having opposite edges each carrying a continuous seal means bearing against the facing surfaces of said panes.

7. The door of claim 6 wherein there are provided spaced brackets on said intermediate member extending from adjacent a frame section to adjacent the opposite frame section and locating means on said opposite frame section loosely engaging said brackets for relative movement therebetween.

8. The door of claim 7 wherein there are provided edge cover means at the outer surface of the outer frame section and the inner surface of the inner frame section hiding said means for yieldably securing a glass pane to its section, the cover means on said other frame section also hiding said pins.
